(57) **CLAIM**

The ornamental design for a table saw cart, as shown and described.

DESCRIPTION

FIG. 1 is a left side perspective view of a table saw cart showing my new design.

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof; and,

FIG. 8 is a left side perspective view thereof of the table saw cart shown in an alternate position.

The broken line showing of the table saw cart is for illustrative purposes only and forms no part of the claimed design.
